UNITED STATES PATENT OFFICE.

AXEL W. NELSON, OF CHICAGO, ILLINOIS.

SANITARY GARBAGE CONTAINER.

Application filed March 26, 1926. Serial No. 97,611.

This invention relates to improvements in sanitary garbage containers and particularly to a device of this character having a suitable hinged cover with convenient foot operated means for operating the same.

The invention comprehends the provision of a concrete container for garbage which is provided with a door in the rear side to permit the insertion and removal of a large garbage can or receptacle to receive the garbage, while the removable top portion has an opening therein, normally closed by a hinged cover having convenient operating means therefor, housed within the container structure and provided with a suitable foot pedal, so that it may be easily operated by the foot for emptying the garbage into the container carried by the receptacle, so that it is not necessary to use the hand in emptying the garbage.

In addition, the invention comprehends the novel construction of container cover and operating mechanism with the associated structure of the concrete container for mounting and housing the same in order that the cover will exclude moisture and yet be easily operable so that garbage may be emptied into the receptacle contained thereby.

The invention includes numerous other objects residing in the construction and arrangement of the parts for carrying out the invention in a most efficient and simple manner, which are more particularly pointed out in the following detailed description and in the claims directed to a preferred form of the invention, it being understood however, that various changes in the size, shape and arrangement of these parts may be made without departing from the spirit and scope of the invention as herein set forth.

In the drawing forming part of this application:

Figure 1 is a side elevation of the container forming the subject matter of this invention, showing portions broken away in order to illustrate the operating mechanism for the cover.

Fig. 2 is a rear elevational view of the container.

Fig. 3 is a plan view thereof.

Fig. 4 is a vertical sectional view taken on the line 4-4 of Fig. 1.

This improved garbage container includes a bottom or container section 1 which includes a bottom 2 and side walls 3, the top of the container being open, and on which

is mounted a cover section 4. The container section 1 and the cover section 4 are formed of concrete molded into suitable shape, and one of the side walls as indicated at 5 is formed to provide inner and outer wall sections 6 and 7 respectively in adjacent spaced relation as shown in Fig. 4 in order to provide the inverted L-shaped recess 8 for housing the operating mechanism for the lid as will be described. These inner and outer wall sections 6 and 7 respectively, are jointed by the connecting portion 9 throughout the central portion of the wall 5 and also at the edge portions as at 10.

The rear wall of the container is formed with an opening 11 to permit the insertion and removal of a suitable receiving receptacle for the garbage which is closed by the doors 12 hinged at 13 to the plate 14 which is suitably secured to the rear wall 3 of the container section. A plate 15 also secured to the rear wall opposite to the plate 14 and adjacent the edge of the opening 11 carries the pivoted latch member 16 which cooperates with the keeper 17 mounted on the door so that this hinged door 12 may be normally held in closed position as illustrated in Fig. 2.

A plate member 18 is mounted adjacent the rear edge of the cover and suitably secured to the cover, such as by bolts or the like 19, and is provided adjacent the opposite ends with pairs of axial aligned sleeve portions 20 which receive the pintle 21 adapted to extend through the sleeve extension 22 on the cover member 23, so as to hinge this cover member to the cover section in order that in the position illustrated in Figs. 1 and 3, it will normally close the opening 24 in the cover section 4, of the container. This cover member 23 is preferably of pyramidal shape so that it will shed moisture, in view of the fact that the container is provided principally for outdoor use. A suitable handle 25 provided on the forward free edge of the cover member 23 so that it may be suitably manually raised if desired.

One side of the cover is provided with an arm member 26 extending beyond the side edge of the cover member to receive the eye 27 of the link 28 which is pivotally connected at its opposite ends to the lever 29. This link member extends through an opening 30 in the cover section 4 communicating with the L-shaped recess 8, while the lever 29 is fulcrumed in its central portion in

said recess as indicated at 30 on a suitable rod section which is embedded in the wall sections 6 and 7 during the formation of the container section 1. The opposite end 5 of this lever 29 is pivotally connected to the operating lever 31 which extends downwardly to the lower end of the recess 8 where it is formed with a lateral extension 32 projecting through the slot 33 in the outer 10 wall section 7 of the container section 1, the terminal of which is looped as indicated at 34 in Fig. 3 to provide a suitable foot lever.

With this construction of garbage container, it will be seen that the hinged door 12 may be readily opened to insert a receptacle for receiving and containing the garbage in the container section 1, and that when it is desired to empty garbage from 20 receptacles usually used in a house, apartment, or the like, into this container, that it is only necessary to place the foot on the loop portion 34 and upon depressing the same, the cover member 23 will be raised 25 so that the garbage may be dumped into the receptacle in the container 1.

This construction is provided for use in apartment houses and the like, so as to protect the garbage from flies and to prevent the 30 escape of odors, and which may be placed in a convenient position for access by the collectors of garbage when it is used in a city, where such collections are made at regular intervals. The lever mechanism for 35 operating the cover member 23 is always housed between the wall sections 6 and 7 and protected against the destructive action of the elements, while the extension 34 provides a convenient foot lever, so that the 40 cover may be conveniently raised and refuse emptied into the receptacle in the container section 1, without touching the container or cover in any way.

Having thus described my invention, what 45 I claim as new is:—

1. A garbage container, comprising a molded container member having a bottom and side walls, said container members being of substantially rectangular in horizon-

tal section, the inner wall formed in spaced 50 parallel relation to one side wall adapted to form a pocket within the container, a cover section formed with a central opening mounted on the upper end of the container member, and closing said pocket, the opening in said cover section communicating with the interior of said container, a cover member hingedly mounted on the cover section for normally closing said opening therein, said container member having the side wall 60 adjacent said inner wall formed with a vertically extending slot communicating with the pocket formed in the member, said cover section having a passage formed therein 65 communicating with said pocket, and operating means for the cover mounted in said pocket having an extension connected with the cover movable through the opening in the cover section and a manually engageable operating projection extending through the 70 slot outwardly beyond the side wall of the container member.

2. A garbage container, comprising a molded container section having a bottom and side walls, a cover section mounted on 75 said container section and having an opening formed therein, a cover member hingedly mounted on said cover section adapted to normally close the opening in said cover section, one wall of said container section being formed with a recess, said cover section being formed with an opening communicating with said recess in the wall of said container section, a link member pivotally connected to the cover member and extending through the opening in said cover section, a lever fulcrumed in said recess having the link member pivotally connected to one end thereof, and an operating link pivotally connected to the other end of said lever having a lateral extension thereon formed to provide a foot pedal, the wall of 80 said container having a slot formed therein to permit the lateral extension on said operating lever to project outwardly beyond 85 the side wall of the container section.

In testimony whereof I affix my signature,
AXEL W. NELSON.
